UNITED STATES PATENT OFFICE.

WILSON ROLLER RUTHERFORD, OF BALTIMORE, MARYLAND.

INTERNAL-COMBUSTION-ENGINE SYSTEM.

1,278,223.

Specification of Letters Patent. Patented Sept. 10, 1918.

Application filed April 30, 1917. Serial No. 165,522.

To all whom it may concern:

Be it known that I, WILSON R. RUTHERFORD, a citizen of the United States, and resident of Baltimore, Maryland, have invented certain new and useful Improvements in Internal-Combustion-Engine Systems, of which the following is a specification.

The invention is designed to supply air and moisture to the intake manifold of an internal combustion engine system adapted for automobiles and it consists in the features and combination and arrangement of parts hereinafter described and particularly pointed out in the claim.

15 The accompanying drawing represents a side elevation of an automobile engine with its carburetor, radiator and intake manifold with my improvement connected up in the system.

20 In these drawings 1 indicates the engine casing, 2 the carburetor, 3 the intake manifold, 4 the radiator and 5 the dash, these parts being of substantially ordinary form.

25 My improvement includes a mixing chamber 6 consisting of a cap member 7, screw-threaded onto a member 8 in the form of a block of cylindrical shape, which is provided with a passage 9 extending from top to bottom of the same and communicating 30 at its lower end with the atmosphere. The upper end of this passage opens into the mixing chamber 6. A second passage 10 extends through the piece 8 and preferably this passage has a lateral branch receiving

35 a short pipe 11 extending through the dash 5 and held thereto by suitable nuts or other means represented at 12. This nozzle has connected with it a pipe 13 suitably supported in fittings 14 attached to the engine 40 casing, the front end of said pipe being connected with the upper portion of the radiator 4 to receive water or vapor therefrom. The angular passage 10 also opens into the mixing chamber 6 and these pas-

45 sages 9 and 10 are disposed at different points around the axis of the piece 8 and their upper openings are controlled by a disk valve 15 carried by a stem 16 extending vertically and substantially centrally of the 50 piece 8 and below said piece, the said stem having a nut or finger piece 17 screw-threaded onto its lower end with a spring 18 interposed between the said nut or finger piece and the bottom of the member 8 so

that the pressure of this spring can be adjusted and its force tending to seat the valve disk and close the openings 9 and 10 can be regulated at the will of the operator, it being observed that the attachment is located at the instrument board or dash within convenient reach of the driver.

From the cap piece 7 of the mixing chamber 6 a pipe 19 extends centrally and upwardly and this has a lateral branch 20 extending to the intake manifold and therefore to a point between the carburetor and the engine.

At the junction of the vertical and lateral portions of this communicating pipe 19, 20 I arrange a needle valve 21, which is screw-threaded through the pipe and extends axially in line with the vertical opening through the pipe 19 leading from the mixing chamber and it is adapted to a seat at the lower end of this vertical passage where it joins the lateral passage. This valve has a kerfed head by which it may be adjusted and set in different positions to regulate the size of the discharge opening between the mixing chamber and the lateral pipe 20.

55 In the operation of the device atmospheric air together with vapor, moisture or water will be drawn into the mixing chamber 6 by the suction created in the pipes 19 and 20 from the intake manifold, this suction action lifting the disk valve 15 and allowing the air and water or moisture to pass into the mixing chamber and this mixture then passes through the regulating needle valve into the pipe 20, the intake manifold and thence to the combustion chambers of the engine. The needle valve renders the appliance applicable to engine systems of different make for by adjusting it the different conditions arising from varying suction as between the different makes may be met, so that in any case a proper lifting of the disk valve may be secured and the use of the spring 18 with the adjustable finger piece or nut 17 provide further regulating elements to control the operation of the valve and by regulating the pressure of the spring the operation of the system may be adjusted to suit varying speeds.

Moreover, I may use different sizes of nozzles to get different amounts of water, vapor or moisture supply and the use of such nozzles will avoid disturbances that

occur ordinarily from the use of the needle valve which under vibration is apt to lose its adjustment.

What I claim is:—

- 5 The combination with a water cooled gasoline driven automobile of a water pipe leading from the top of the radiator through the dash and suitably supported from the engine casing, nuts threaded on said pipe
- 10 and clamping the dash therebetween, a cylindrical block having a port in its side threaded to engage the end of said pipe, said block having a flat upper face and a passage leading from said port to said upper face,
- 15 an air passage extending vertically through

said block, a hollow cap in threaded engagement with the upper end of said cylindrical block, said block having a central passage, a disk valve overlying the upper face of the block and having a stem depending through 20 said central passage, a nut on the lower end of the stem, a spring confined between said nut and the lower face of the block, a pipe elbow having one arm connected to said cap, a screw valve in said elbow, and a pipe connecting said elbow with the intake manifold of the engine, substantially as described. 25

In testimony whereof I affix my signature.

WILSON ROLLER RUTHERFORD.
